UNITED STATES PATENT OFFICE.

JAMES W. HOLLENBECK, OF RIOVISTA, CALIFORNIA.

SPUD-GRIP FOR DREDGERS, &c.

SPECIFICATION forming part of Letters Patent No. 786,968, dated April 11, 1905.

Application filed December 6, 1904. Serial No. 235,688.

To all whom it may concern:

Be it known that I, JAMES W. HOLLENBECK, a citizen of the United States, residing at Riovista, in the county of Solano and State 5 of California, have invented new and useful Improvements in Spud-Grips for Dredgers or the Like, of which the following is a specification.

My invention relates to an improved grip 10 for the spuds of dredges, pile-drivers, and the like.

It is common to employ on dredges and elsewhere for the purpose of raising and lowering the spuds or timbers by which the vessel is anchored a form of grip which consists of a rectangular closed yoke or band adapted loosely to embrace a spud and having an eye or other means on one side for the attachment of a cable or block and tackle. While 20 this grip has the merit of simplicity, it is objectionable in that it does not always hold the spud securely, and by reason of its more or less sharp or narrow edges jamming into opposite sides of the spud rapidly wears away 25 the latter and sometimes even breaks the spud in two.

The object of my invention is to provide a durable, powerful, practical grip, which will invariably take a firm hold on the spud and 30 will not slip, which will not cut or destroy the spud, and which shall be simple and can be quickly applied.

The invention consists of the parts and the construction and combination of parts, as 35 hereinafter more fully described and claimed, having reference to the accompanying drawings, in which—

Figure 1 shows the application of the preferred form of my device. Fig. 2 is a section 40 on line *z z* of Fig. 1. Fig. 3 shows a modification of the invention. Fig. 4 is a section on line *y y* of Fig. 3.

My grip comprises, essentially, an open 45 toggle-frame or double toggle connected at the ends and joints adapted to be slipped over the end of a spud or timber and having suitable bearing parts disposed between the spud and the opposite sides of the toggle, where the pressure comes on the spud.

As shown in Fig. 1, A and B represent two

yokes hinged together at one side by the bolt 2 to form a toggle and corresponding in shape and size to the spud or timber, as 3, with which the grip is assumed to be used in conjunction. A bearing-plate 4 of a width approximately equal to that of the spud is hinged, as at 5, to the front of the lower yoke and is of sufficient length to extend up inside of yoke A and in front of a roller 6, carried by said yoke, and to lie between this roller and the spud when the grip is slipped over the spud. When the grip is engaged with a spud, one member has a limited pivotal movement relative to the other. As they open out they grip the spud and as they close together they 65 release it. The forward end of the member A is provided with suitable means, as the eye 7, for the attachment of a block and tackle or a line, so that when the member A is lifted and the front of member B dropped the roller 6 will bind on the bearing-plate 4 adjacent to the top of the latter. The hinge-bolt 2 preferably carries a shoe 8, which may be of any suitable size and area to engage the back of the spud and relieve the latter of the immediate and otherwise destructive pressure of bolt 2. Where shoe 8 is pivoted to the bolt, as here shown, the movement of the shoe about the bolt may be limited by suitable means, as the pin 9, so that the proper bearing-surface of the shoe will always be presented without difficulty to the spud. The 70 two yokes operate as a toggle-grip to engage the opposite sides of a spud or other object to be gripped, and the inward pressure exerted by the toggle is distributed over a comparatively large area by reason of the interposed parts 4 and 8. The yokes may be of any suitable size or construction, optional with the manufacturer. In the present instance each yoke is shown as made up of separate pieces bolted together and suitably spaced to form rigid, strong, and durable and at the same time very simple structures. The part 75 4 may be made of boiler-plate, to which are riveted the straps or bands, having their lower ends bent around the front of the yoke B to form the hinges 5. The lower yoke B has the elongated slots 10, through which the bolt 2 passes, to allow for the suitable 80

enlargement of the space within the yokes, to let the grip be easily slipped over the spud, and to permit the latter when released by the grip to readily pass through the latter 5 without any hindrance. By this construction of grip a sure and powerful hold may be taken on a spud, and the compressive strain on the spud exerted by the grip will be distributed over a considerable area, so that 10 no damage will be done the spud. The grip can be moved to any point on the spud and will always take hold with equal readiness and security. The instant the grip contacts with suitable stops, as 11, disposed in its 15 path and tension on the upper yoke is released, the grip immediately opens to free the spud and allow the latter to drop. The upper and lower edges of the plate 4 and shoe 8 are curved outward or flaring, so as not to 20 dent, catch on, or splinter the spud.

In Fig. 3 is shown a slightly-modified form of my device, in which the shoe 8' is elongated and is constructed similar to the bearing-plate 4 of Fig. 1, but with the upper ends 25 of the parts 8' and 4' connected by links 12, extending on opposite sides of the spud. The operation of the grip is essentially the same as in the first instance.

It is possible that various modifications in 30 my invention may be made without departing from the principle thereof, and I do not wish to be understood as limiting myself to the specific construction as herein shown and described.

35 Having thus described my invention, what I claim, and desire to secure by Letters Patent, is—

1. A toggle-grip for spuds and the like, one of the members of said toggle having 40 means opposite its jointed end for the attachment of a cable or other means of support.

2. A toggle-grip comprising two hinged yokes.

45 3. A toggle-grip comprising two yokes hinged together at one side and adapted to be freely slideable on a spud or the like.

50 4. A grip comprising two substantially rectangular frames hinged together at one side and having a limited pivotal movement

relative to each other when slipped over a spud.

5. A grip comprising two yokes hinged together at one side, bearing-plates carried by the yokes and interposable between the same 55 and the article to be gripped.

6. A grip comprising two yoke members pivotally connected at one side, a bearing-plate carried by one member and extending upward within the other member, said members having a limited movement relative to each other when embracing the object to be gripped.

7. A grip comprising two yoke members pivotally connected at one side, a bearing- 65 plate connected to one of the members opposite to the pivoted side, said bearing-plate extending upward within the other member but disconnected therewith, and a part carried by said other member and adapted to engage said bearing-plate when the members are operatively engaged with the object to be gripped.

8. A grip comprising a toggle having two yoke members hinged together at one side, 75 one of said members having a limited reciprocating movement independent of the other and bearing parts carried by the members and interposable between the latter and the object to be gripped.

80 9. A gripping device comprising two hinged yokes provided with bearing-plates interposable between the yokes and the part to be gripped, and means carried by one of said yokes for the attachment of a block and 85 tackle or other suspensory means.

10. A grip comprising two hinged yokes, a shoe carried by the hinge, a bearing-plate opposed to said shoe and supported by one of the members and interposable within the 90 other member when the two are engaged with an object to be gripped.

In testimony whereof I have hereunto set my hand in presence of two subscribing witnesses.

JAMES W. HOLLENBECK.
